STRIKING LINE HOLDER

Roy J. Pomeroy, Los Angeles, Calif., assignor to
Octave B. Clarke, Los Angeles, Calif.

Application October 6, 1943, Serial No. 505,212

5 Claims.

(Cl. 33—87)

This invention relates to striking line holders such as are employed by carpenters for marking lines on surfaces, by shipfitters for marking deck plates and the like, and in similar situations wherein a line is to be indicated on a surface as a guide for workmen or artisans.

It is the present practice in some shipyards to mark a line on deck plates by using a chalked cord that is extended over the area to be marked. This cord is then snapped against the surface of the plate to transfer chalk from the cord to the surface of the plate. But as the chalked line formed on the plate is not definite and permanent in its nature, its position on the plate is then marked by using a punch such as the common center punch to form a line of indentations in the plate; after which, in case the marked plate is not to be worked on immediately, it is the practice to daub paint near the indentations. This procedure involves a considerable number of time-consuming operations. Moreover, even with the paint marks daubed on near the indentations, the indentations are frequently somewhat difficult to find at a subsequent time.

An object of the present invention is to provide a strike-line holder and reel for a cord that is capable of making a more permanent mark on such a surface, and which will eliminate the necessity for using the center punch indentations and the operation of daubing spots of paint in their vicinity, as well as the subsequent search for the paint spots and indentations marked thereby.

The invention provides an improved striking line holder involving the use of a liquid marking substance having a color contrasting with the color of the surface being marked, and for this purpose, I may use a liquid lacquer, or any other suitable marking liquid capable of marking a clean and relatively permanent visible line.

Another object of the invention is to provide simple means for exerting a squeezing effect on the cord to remove the excess liquid marking substance, and which is so constructed and arranged that the cord will move freely through it when passing into the holder and onto the reel.

In the preferred embodiment of the invention, I provide a guide pulley located opposite to the outlet, and one of the objects of the invention is to provide simple braking means for preventing racing of the reel to insure that the cord will be maintained against the pulley as it comes off the reel and moves toward the squeegee that removes the excess marking liquid from it.

Another object of the invention is to provide a simple construction for housing the coil spring that maintains the brake pressure in the reel, and a further and more general object is to improve the general construction of a striking line holder of the character mentioned.

This invention consists in the novel parts and

organization of the parts described herein and more particularly set forth in the accompanying claims.

In the accompanying drawing illustrating a preferred embodiment of the invention:

Fig. 1 is a vertical section through the device with a portion of the spring housing shown in elevation, taken about on the line 1—1 of Fig. 2;

Fig. 2 is a vertical section taken about on the line 2—2 of Fig. 1;

Fig. 3 is a fragmentary section showing the upper portion of Fig. 2 upon an enlarged scale, and broken away. This view shows the squeegee in its release position, that is, the position it assumes when the cord is running freely in onto the reel; and

Fig. 4 is an end view of the spring housing and handle, with the outer portion of the casing broken away. This view shows certain parts associated with the brake-spring broken away and partially in section.

In practicing the invention, I employ a holder casing 1 of the drum form that may be conveniently made of sheet metal, the interior of which forms a closed chamber for a marking liquid.

The cord 2 that wraps on a reel 3 within the casing can be drawn off at will through outlet means which in the present instance includes an opening 4 through the circumferential wall 5 of the casing.

The reel 3 may consist of a spool having two separated flanges 6 connected by an integral neck and provided with a skeleton type body on which the cord wraps, composed of equidistant pins or small bars 7.

Opposite and in line with the opening 4, I prefer to provide a guide pulley 8 which in the present instance consists of a long spool. This enables the pulley to guide the cord properly regardless of where it is coming off the reel.

In the path of the cord as it passes to the opening 4, I provide a device 9 that I call a squeegee, as its function is to remove excess liquid from the cord. In the present instance, it consists of a flat bar that is movably mounted, preferably to swing on a pivotal axis at 9a, and it has means for exerting a squeezing effect on the cord. With the simple construction shown, the part 9 is formed with a drill hole 10, disposed preferably at right angles to the bar, through which the cord passes. With the bar 9 in the position of Fig. 3, this hole 10 is in line with opening 4 and with pulley 8. When the cord is being pulled out of

the casing the tension in the cord pulls the bar 9 up to an angular position against a stop 11, preferably in the form of a set screw. This set screw enables the working position of the squeegee to be adjusted to regulate its squeezing effect. When against the stop 11 the axis of the hole 10 is substantially out of line with the path of the cord,

60

thereby causing the cord to be bent slightly as it passes, and so causing a portion of the liquid lacquer to be expressed from the cord.

An inner, fixed stop 12 is provided to prevent the bar 9 from resting on the guide roller 8, which would interfere with its free rotation, and to establish the right angle position of the bar during the ruling-in operation.

The cord 2 should be wound on the reel in the direction indicated in Fig. 2 so that the pulley 8 acts as a guide for it, but in order to insure this, and prevent the reel from racing so as to carry the take-off point of the cord over to the right and off the pulley, I prefer to provide a resistance device for the rotation of the reel. This preferably consists of a brake disc 13 that is spring-pressed against the side of the casing. This disc is mounted nonrotatively on a neck 14 that extends out from the trunnion 15 of the reel, which trunnion is rotatably mounted in the adjacent end wall of the casing. This neck 14 may have flat side faces 16 (see Fig. 4) between circumferential faces, and the brake-disc 13 has a sleeve on the trunnion 15 with a reduced extension sleeve 17 having an opening through it that is shaped to fit to the neck 14. At the root of the extension sleeve 17 a shoulder 18 is formed operating as a seat for a light coil spring 19. The end of the neck 14 carries a stud 20, with a nut 21 for holding the spring housing 22 over the spring. The housing 22 has a bore 23 forming a chamber for the spring 19, and fitting over the sleeve of the brake disc 13. It should be noted that while the spring presses the brake 13 against the casing, it also pulls the adjacent head 6 of the reel against the inner face of its end wall.

The housing 22 also operates as a knob or handle for supporting the holder and may be rotated to wind up the cord on the reel. When this occurs, the cord will pull the bar 9 down against the fixed stop 12 (Fig. 3). This is the release position for the squeegee and brings the axis of the hole 10 into substantial alignment with the path of the cord so that the cord will run freely through it onto the reel.

At the outlet opening 4 from the casing, and preferably on the outer side, I provide a fitting 24 with a stuffing box 20 in it to hold a soft wiper such as raw cotton or other suitable absorbent material. This wipes off any excess of the liquid that may be slinging to the surface of the cord. A ball-head plug 24a may be used to retain this cotton.

The casing is provided with suitable means for replenishing the liquid within it. In the present instance, one of the ends or heads of the casing is provided with an integral sleeve 26 coaxial with the casing and formed with a spun thread to receive a screw cap 27.

In operating the device, the cord is pulled out from the casing over the line that is to be marked off. As it comes out of the casing the tension in the cord pulls the squeegee 9 into its operative position indicated in Fig. 2. As the cord pulls through the inclined hole 10, the excess liquid is squeezed out of it, and as it passes through the stuffing box 24 its outer surface is wiped off.

After being extended over the surface to be marked, the cord is held taut and snapped against the surface to mark it.

When the cord is being wound onto the reel, the pull of the cord swings the squeegee into its release-position indicated in Fig. 3, in which the cord will run freely through the hole 10.

Many changes may of course be made in the

construction illustrated and described, without departing from the spirit of the invention.

I claim:

1. A striking-line holder including a casing having a chamber therein; a reel for carrying a marking cord wrapped thereupon; said casing having means for holding a marking liquid so as to transfer a portion of the same to the cord; means for effecting the guiding of the cord to the exterior of the casing when the cord is being extended over a surface that is to be marked, including an opening in the casing wall through which the cord passes, and a guide for the cord opposite said opening; and a squeegee supported between the said guide and said opening so that it is capable of moving toward the outlet when the cord is running out, and toward said guide when the cord is running in, said squeegee having a guide passage therethrough for the cord the axis whereof is disposed substantially in line with said guide and the opening when the cord is running in, and substantially out of line with the said guide and the opening when the cord is running out, said squeegee operating in the latter position to remove excess liquid from the cord as it passes out.

2. A striking-line holder including a casing for holding a liquid and having an outlet for the cord; a reel for the cord rotatably mounted in the casing and a squeegee operable on the cord between the reel and the outlet, said squeegee embodying a movably mounted cord-engaging member movable to a position to express excess liquid from the cord by virtue of movement of the cord in a direction from the reel to the cord outlet, and movable to a position to release the cord for free running action by virtue of movement of the cord in a direction from the cord outlet toward the reel.

3. A striking-line holder including a casing for holding a liquid and having an outlet for the cord; a reel for the cord rotatably mounted in the casing; and a squeegee operable on the cord between the reel and the outlet, said squeegee embodying a cord-engaging member movably mounted on said casing and movable between one position in which it deflects the cord and so operates to express excess liquid from the cord, and another position in which it releases the cord for free running travel, and being arranged to automatically assume the former of said positions by virtue of travel of the cord from reel toward cord outlet, and the latter of said positions by virtue of travel of the cord from cord outlet toward reel.

4. A striking-line holder including a casing for holding a liquid and having an outlet for the cord; a reel for the cord rotatably mounted in the casing; a squeegee movably mounted in the path of the cord, having an opening through which the cord passes, said squeegee being mounted and arranged for movement by virtue of travel of the cord out of the casing to a position in which it deflects the path of the cord and thereby expresses liquid therefrom, and for movement by virtue of travel of the cord inward of the casing into a release position wherein it releases the cord for free undeflected travel therewith.

5. A striking line holder according to claim 4, in which the squeegee includes a pivoted bar; and a stop cooperating with said bar to limit the pivotal movement of said bar in moving to said position in which the path of the cord is deflected.
